LAURENCE J. BERKELEY, OF RACINE, WISCONSIN, ASSIGNOR TO HERCULES MANUFACTURING COMPANY, OF RACINE, WISCONSIN, A CORPORATION OF WISCONSIN.

SPIKE-MACHINE.

1,345,064.

Specification of Letters Patent. Patented June 29, 1920.

Application filed May 10, 1918. Serial No. 233,715.

To all whom it may concern:

Be it known that I, LAURENCE J. BERKELEY, a citizen of the United States, residing at Racine, in the county of Racine and State 5 of Wisconsin, have invented certain new and useful Improvements in Spike-Machines, of which the following is a specification, reference being had to the accompanying drawing, forming a part thereof.

- 10 This invention relates to machines of the type shown and described in my application Serial No. 210,599, filed January 7, 1918, for forming spikes with points, bodies and heads of various or any desired shapes.
- 15 The main objects are to facilitate the production of spikes by first rolling and forming the bodies with the points foremost and cutting to length from continuous blanks or bars of substantially uniform cross section 20 and then forming heads on the formed and severed bodies without reversing them in the machine; to provide for the formation of spikes with so-called "dog-eared" heads as well as with heads of other shapes; and 25 generally to improve the construction and operation of machines of this class.

It consists in the construction, arrangement and combination of parts as herein-after particularly described and pointed out 30 in the claims.

In the accompanying drawing like characters designate the same parts in the several figures.

Figure 1 is a plan view of the spike machine embodying the invention, parts being removed and other parts broken away; Fig. 2 is a vertical longitudinal section of the machine on the line 2—2, Fig. 1; Fig. 3 is a fragmentary side elevation as viewed 35 from the right relative to Fig. 5; Fig. 4 is a vertical cross section on the line 4—4, Fig. 2; Fig. 5 is a similar cross section looking in the opposite direction on the line 5—5, Fig. 2; Fig. 6 is an enlarged vertical 40 section on the line 6—6, Fig. 7 of the heading dies; Fig. 7 is an enlarged front elevation of said dies as viewed from the left relative to Fig. 6, and a vertical section of 45 associated parts of the frame on the line 5—5, Fig. 1; Fig. 8 is an inverted plan view of the vertically and laterally movable heading dies; Fig. 9 is an enlarged vertical cross section on the line 9—9, Fig. 1 of one side 50 of the jaw carriage, showing one of the 55 clamping jaws and its adjustable link con-

nctions with the carriage; Fig. 10 is an enlarged cross section on the line 10—10, Fig. 9, of one of the links; Fig. 11 is an enlarged longitudinal section of one of the body forming and pointing die rolls; Fig. 12 is a vertical longitudinal section on the line 12—12, Figs. 1 and 13, of one of the air cushion retarding connections of the nipper frame; Fig. 13 is a plan view of the cushion cylinders and their connections, and Fig. 14 is 60 a cross section on the line 14—14, Fig. 11.

In the following description of the construction and operation of the machine, the end adjacent to which the body forming and pointing die rolls are located is regarded as 70 the front end, and movements of the work and working parts of the machine toward the opposite end of the machine adjacent to which the main drive shaft is located, are regarded as advance or forward movements 75 while movements in the opposite direction are regarded as backward movements.

The machine comprises a pair of shoudered body forming and pointing die rolls 80 1 and 2, mounted one above the other on parallel horizontal shafts 3 and 4, which are provided with bearings in the frame 5.

As shown in Figs. 2, 11 and 14, the rolls 1 and 2 are each provided with a series of hardened steel body forming and pointing 85 dies 6, which are detachably fastened with shouldered and radially slotted die and spacing rings 8, to the rolls, by cap rings 9 and screws 10 and 11. The screws 10 pass through the rings 8 and 9 between the dies 90 6, and are threaded in the rolls, while the screws 11 are threaded in the cap rings 9 and engage with the dies, clamping them to the rolls. In the present case the dies 6 are shown as designed to produce straight 95 or plain spike bodies with chisel points at one end, but may be replaced by dies for making bodies of various forms, particularly of abruptly varying cross section, as shown and described in my former application 100 above mentioned. The dies of both rolls are correspondingly spaced and arranged in the same vertical plane so as to register exactly in pairs on the approaching sides of the rolls between which the spike 105 bars or blanks are fed.

The shafts 3 and 4 are connected at one end by gears 12 and 13, by which the rolls are compelled to rotate in opposite directions at the same peripheral speed. At the 110

opposite end the lower shaft 4 is provided, as shown in Figs. 1 and 4, with a ratchet wheel 14 and an oscillatory pawl carrier 15, to the upper end of which a pawl 16 is pivoted.

The bearings of the upper shaft 3 are vertically adjustable by means of screws 32, to set and hold the dies 6 of the upper roll at the desired distance from the opposing dies of the lower roll.

The rolls are intermittently rotated to bring successive pairs of dies into working position by the oscillation of the pawl 16, which is actuated from the main drive shaft 15 17 at the opposite end of the machine through a crank or eccentric 18, mounted on said shaft, a rod 19 connecting the crank pin or eccentric with the upper end of a rocker arm 20 fixed on a cross shaft 21, and 20 an adjustable rod 22, connecting the lower end of the rocker arm 20 with the lower end of the pawl carrier 15.

As shown in Figs. 1 and 2, a reciprocating carriage 23, is mounted on horizontal ways 24, formed on or attached to the sides of the frame 5 between and transversely to the axes of the rolls 1 and 2, and is connected by rods 31, with upwardly extending rocker arms 25, fixed on the shaft 21.

30 Laterally or transversely opening and closing clamping jaws or dies 26, are mounted on the carriage 23, and are movable therewith forward and back alongside the roll dies 6, with which they coöperate during each simultaneous advance movement of the rolls and jaws, to form the shanks or bodies and points of spikes from continuous bars or blanks. The carriage 23 is capable of a limited longitudinal movement relative 35 to and independently of the jaws 26, the extent of such movement being determined by fixed stops 27 and adjustable stop screws 28, with which the carriage is provided adjacent to opposite ends of the jaws.

40 The jaws are connected by transversely disposed links 29 with transversely adjustable pivot blocks 30, which are guided in openings in the carriage and are adjusted transversely to its travel by wedges 33, 45 which in turn are adjusted lengthwise by screws 34, to determine and regulate the degree of approach of the jaws toward each other, and their proper relation to the roll dies 6.

50 55 Spiral springs 35, interposed between the inner sides of the pivot blocks 30 and the inner walls of the openings in which they are guided, yieldingly hold the blocks against the wedges, and enable the links 29, 60 when they are turned as shown in Fig. 1 into positions oblique to the axes of the roll shafts, to withdraw the jaws from each other. The stop screws 28 are adjusted to engage with the jaws 26 when the links 29 65 have been turned by the initial advance

movement of the carriage with the pivot blocks 30 into positions substantially parallel with the axes of the roll shafts, and have thus shifted the jaws to the limits of their movement toward each other.

The link connections between the jaws 26 and pivot blocks 30 are preferably constructed and arranged as shown in Figs. 9 and 10, in connection with Fig. 1. The links 29 are arranged in parallel pairs above and below the jaws and pivot blocks, and the links of each pair are pivotally connected therewith by pins 36 and 37, projecting above and below the jaws and blocks. Each link is composed of a strut member 38, having longitudinally grooved sides and semi-cylindrical recesses in the ends fitting opposite pivot pins 36 and 37; a yoke 40, formed with a semi-cylindrical recess fitting the pin 37 and with holes matching the 85 grooves in the strut member at its outer end; and a U-bolt 41, passing around the pin 36 and through the yoke in engagement with a groove in said pin and with the grooves in the strut member, and binding the 90 several parts together. The strut members 38 receive the direct thrust on the links in closing the jaws 26 against the spike blanks with the initial advance movement of the carriage 23, and in confining and shaping 95 the blanks as they are advanced with the jaws between the dies 6. The links being placed above and below the jaws and pivot blocks equidistant therefrom, equally and symmetrically distribute the side thrust 100 against the jaws in forming spike bodies, and hold the jaws in place against any tendency toward upward or downward displacement thereof.

A reciprocating nipper frame comprising 105 parallel side members 44, guided in longitudinal channel ways 45, extending inwardly from the sides of the frame 5, as shown in Figs. 1, 2 and 4, is provided with laterally movable nippers 46, located on opposite sides 110 of the path of the spike blanks or bodies as they are advanced by and delivered from the roll dies 6 and the jaws 26. The nippers are pivoted at 47 to the side members 44 of the nipper frame adjacent to its front end, 115 from which they extend and converge toward the jaws 26, and are formed or provided with arms 48 extending rearwardly underneath said side members through the ways 45, and are provided at their rear 120 ends with inwardly and rearwardly inclined slots 49. The side members of the nipper frame are longitudinally channeled on the under side, and in their rear ends are loosely fitted and guided, bars 52, which are connected by links 53 with rocker arms 54, fixed at their lower ends on a cross shaft 55 having bearings depending from the sides of the frame 5, as shown in Figs. 1, 2 and 5. The bars 52, which bear on the upper sides 125

of the nipper arms 48, as shown in Fig. 4, are provided with downwardly projecting pins 56, which engage with the inclined slots 49 in the nipper arms, for opening and closing the nippers, as hereinafter explained.

As shown in Figs. 1 and 3, the shaft 55 is provided at one end outside of the frame 5, with an arm 60, which is connected by a link 61 with an arm 62 on the adjacent end 10 of the shaft 21. The arm 60 has an adjustable pivot block 63, with which the link 61 is connected, and which is adjusted by means of a screw rod 64, and the link 61 is provided with a pivot block 65, which is adjustable by means of screws 66 lengthwise of the link, and is connected with the arm 62 for varying the throw of the rocker arms 25 and the extent and limits of the longitudinal traverse of the nipper frame and nippers 46.

As shown in Figs. 1, 2 and 4, friction shoes or blocks 70, freely fitting in openings in cap plates 71, bolted to the ways 45 over the side members 44 of the nipper frame, 25 are held with yielding pressure against said members by springs 72, interposed between them and vertically adjustable bars 73, connected by threaded studs 74 and nuts, with said plates.

30 The nipper frame is adjustably connected at its rear end, as shown in Figs. 1, 2, 12 and 13, by rods 67 with check pistons 68 which are fitted and work in air cushion cylinders 69, attached to the frame 5. The 35 pistons are formed as shown in Fig. 12, with restricted by-pass openings 75, and the cylinders are connected with each other and with the atmosphere, as shown in Fig. 13, by equalizing pipes 76 provided with regulating valves 77.

The rear links 29, for opening and closing the jaws 26, are connected by links 78 with drag bars 79, guided and longitudinally movable in bearings formed therefor 45 in the front ends of the cap plates 71. The bars 79 are confined in said bearings by friction plates 80, which are bolted to the plates 71 and are yieldingly pressed and held against said bars by springs 81, inserted 50 between the bolt heads and friction plates, thereby providing drag or retarding connections between the jaws 26 and stationary parts of the machine for opening and closing the jaws at the beginning of the backward and forward movements of the carriage 23.

60 The machine is provided with heading mechanism, to which the spike bodies are transferred directly without reversal, from the body forming and pointing rolls 1 and 2 and jaws 26. The heading mechanism comprises, as shown in Figs. 1, 2, 4, 5, 6, 7 and 8, a stationary die 83, fitted and secured by cap plates 84 and screws in the front end 65 of a longitudinal recess formed in a bed or

cross piece 85, spanning the space between the ways 45. The die 83 is formed, as shown in Fig. 7, with opposing or upwardly diverging longitudinal inclines 86. A vertically movable head 87 is provided on the 70 under side with a relatively fixed die 88, and on opposite sides thereof with laterally movable dies 89.

For convenience in constructing, assembling and replacing parts, the intermediate 75 fixed die 88 and the laterally movable side dies 89, are mounted on a block 90, detachably bolted to the lower side of the head 87. The die 88 is fitted into a longitudinal recess in the under side of the block 90, to 80 which it is detachably fastened by screws, as shown in Fig. 6, and the dies 89 are fastened by screws, one to a transverse slide 91 and the other to two parallel slides 92, between which the slide 91 is fitted. The several slides 91 and 92, which are of the same thickness vertically, are guided in a transverse channel formed in the under side of the block 90, and are held in place therein by the die 88 and by plates 93, bolted to the 90 block across the channel.

The dies 89 are formed on their outer sides with downwardly converging longitudinal inclines 94, corresponding with the inclines 86 on the stationary die 83, with 95 which they co-operate to close the dies 89, or force them together when the head 87 is forced downward toward the stationary die, as shown in Fig. 7. Bowed leaf springs 95, interposed between the die 88 and the 100 dies 89, which are recessed on their inner sides to permit them to close or approach each other below the die 88, as shown in Fig. 7, tend to open or separate the dies 89 when they are raised out of engagement 105 with the die 83.

The head 87 is attached to a plunger or slide 97, which is guided, as shown in Figs. 2 and 4, in a stand 98, mounted on and extending across the frame 5. The plunger or 110 slide 97 is connected with the stand above it by springs 99, which tend to lift it with the dies 88 and 89, and to hold them normally in an elevated position above the stationary die 83.

Between the upper end of the plunger 97 and a vertically yielding pivot bearing 100, guided in the stand 98 above and in alignment with the plunger, a toggle joint 101 is interposed for forcing the plunger with the 120 dies 88 and 89 downward against the tension of the springs 99. The bearing 100 engages at its upper end with a spring seat 102, normally resting on the stand 98, and between this seat and a similar seat 103, adjustably 125 connected by a yoke 104 and tie rods 105 with the stand, as shown in Fig. 4, is interposed a heavy spiral spring 106, which receives the end thrust on the plunger 97 when it is forced with the dies 88 and 89 by the 130

toggle joint 101, downward against the stationary die 83 and spike bodies deposited thereon.

The knuckle pivot between the members 5 of the toggle joint 101, is connected by an adjustable forked rod 108, with the upper end of a forked rocker arm 109, which is fixed on a cross shaft 110, supported in bearings on the sides of the frame 5, as shown 10 in Figs. 1, 2 and 5.

The arm 109 is provided with rollers 111, engaging cams 112, fixed on the main drive shaft 17. An adjustable spring 115, interposed between the frame 5 and an arm 116 15 which is fixed on the shaft 110, tends to bend the joint 101 to the right, as shown in Fig. 2, and to hold the rollers 111 in engagement with the cams 112.

The rod 108 is supported adjacent to the 20 toggle joint 101 by a counterbalancing spring 117, connecting it with an arm or bracket on the stand 98.

A swaging die 120, adapted to coöperate with the dies 83, 88 and 89, which serve as 25 gripping and holding dies for forming heads on the spike bodies, is fitted and detachably fastened in a recess in the upwardly offset front end of a longitudinally reciprocating header bar 121, which is supported by rockers 122 and 123, as shown in Figs. 1, 2, 4 and 30 5. The rocker 122 is pivotally mounted on a cross rod or shaft 124, supported at the ends by arms 125, which are pivoted at one end to the frame 5 and are provided at the other 35 end with adjusting screws 126 bearing on said frame. The rocker 123 is mounted on a cross rod or shaft 128, which is supported at its ends in the sides of the frame 5. Near its rear end the header bar 121 is connected 40 by a forked rod 130 with a crank or eccentric 131, with which the drive shaft 17 is provided between the cams 112. A shouldered buffer block 133, fitted in the bed 85 behind the stationary die 83, and extending above 45 the same, as shown in Fig. 2, and a cross bar 134 mortised at the ends into the ways 45 and engaging the shoulder on the back side of said block, are adapted to support the gripping and holding dies 83, 88 and 89 at 50 their rear ends, and to receive the impact of the blows delivered by the swaging die 120 against their front ends in the operation of forming heads on spike bodies, as shown in Fig. 6, the gripping and holding dies at 55 their front ends and the swaging die being properly formed to produce heads of any desired shape.

The nippers 46, located between the rolls 1 and 2, and the gripping and holding dies 60 83, 88 and 89, traverse a somewhat longer path than the clamping jaws 26, and advance simultaneously therewith at a more rapid rate, so as to sever and separate the spike bodies grasped and carried forward by 65 the nippers from the bars or bodies held be-

tween the jaws 26 during their advance. The stationary die 83 is located directly below the vertically movable die 88 in position to receive the severed spike bodies delivered by the nippers 46 at the forward limit of 70 their movement, as hereinafter explained.

The header bar 121, which is of angular form as shown in Fig. 2, extends forward underneath the bed 85, and is upwardly bent or offset at its front end, which traverses an 75 oblique path between the front end of the die 83 and the lower roll 2, causing the swaging die 120 near the limit of its upward and forward movements, to strike the butt ends of spike bodies held between the dies 83, 88 80 and 89 with sweeping or glancing blows, and form heads of the desired shape thereon according to the configuration of the dies. In its downward and backward movements the die 120 passes below the path of the nippers 85 and spike blanks or bodies held between them.

A guide 135, shown in Figs. 1 and 2, is attached to the frame 5 in position to support the spike bodies as they are delivered 90 from the rolls 1 and 2 and are grasped by the nippers 46.

A reciprocating channeled ejector 137, connected by a link 138 with the header bar 121, and guided in a longitudinal groove and opening in the block 133 below the cross bar 134, is adapted on the backward movement of the header bar 121 when the dies 88 and 89 are elevated, to remove the previously headed spikes from the die 83.

At the front end of the machine, a flanged roller 140, is mounted on a cross rod or shaft 141, to assist the operator in properly directing spike bars or blanks between the rolls 1 and 2.

In the operation of the machine, a spike blank or bar, rested on the roller 140, is inserted by the operator between the rolls 1 and 2 and between the jaws 26, during or at the end of the backward movement of the carriage 23, when the jaws are open. At the beginning of the advance movement of the carriage, the jaws are closed against and firmly grip the sides of the spike blank or bar, which is then carried forward between 110 opposing dies 6, the jaws and dies advancing at the same rate of speed and coöoperating to form the point and body of a spike. At the limit of the advance movement of the carriage and jaws 26, the rolls are simultaneously stopped and dwell till the carriage returns to its initial position and the pawl is turned backward with the rocker 15, to engage another tooth of the ratchet wheel 14. With the initial backward movement of the 115 carriage, the jaws 26 are held stationary by the action of the friction plates 80 on the bars 79 till the outer ends of the links 29 are swung backward by the backward movement of the pivot blocks 30 and the jaws 120 130

are opened or separated, as shown in Fig. 1, whereupon they are engaged by the stops 27 and then carried backward with the carriage. With the initial forward movement of the carriage, the jaws 26 are held stationary by the friction plates 80 till they are engaged by the stop screws 28, and the outer ends of the links 29 are swung forward, thereby closing the jaws against the spike blank or bar preparatory to pointing and forming another spike body.

The pawl 16 on its backward movement, is carried beyond the next tooth of the ratchet wheel 14 a distance corresponding with the initial movement of the carriage required to close the jaws 26 and advance the stop screws 28 against them, so that the opposing dies 6 and the jaws coöperating therewith, start forward together and the actuating connections of the pawl and carriage with the drive shaft 17 are such that the jaws and the rolls stop simultaneously at the limit of each advance movement thereof.

The spike blank or bar being firmly gripped and held at the sides between the jaws 26 while the points and bodies of spikes are being formed, the tendency of the spike bodies as they are delivered from the roll dies to bend upward or downward and follow either of the rolls, is counteracted, and lateral displacement of the metal is prevented. The spike bodies being rolled and formed with the points foremost, the displacement of metal required to form the points and bodies is rearward before succeeding portions of the dies are brought close enough together to prevent such displacement, lateral displacement of the metal being prevented by the jaws.

The pointing and formation of spike bodies of various shapes, particularly those of abruptly varying cross section, are thus facilitated and made possible by rolling the points first, it being impossible to satisfactorily point and roll bodies of abruptly varying cross section butt first.

During the dwell of the rolls 1 and 2 and dies 6, and the backward movement of the clamping jaws 26 with the carriage 23, the nipper frame is moved backward. With the initial backward movement of the bars 52, the nipper frame being held stationary by the action of the friction blocks 70, the nippers 46 are opened or separated by the action of the pins 56 in the oblique slots 49 of the nipper arms 48, and then by the engagement of said pins with the divergent front ends of the slots when the nippers are fully opened, the nipper frame is picked up and carried backward with them.

With the initial advance movement of the bars 52 while the nipper frame is held stationary by the friction blocks 70, the nippers are closed by the action of the pins 56

in the slots 49, and tightly grip the previously formed spike bodies close to the jaws 26, which are at or about the same time closed against another section of the spike blank or bar preparatory to the formation of another spike body. The nippers being thus closed, are advanced with the nipper frame simultaneously with the advance of the jaws 26 and the coöperating roll dies 6.

In the advance movement of the friction actuating bars 52, the nipper frame is picked up and carried forward with the nippers before the pins 56 engage the convergent rear ends of the slots 49, whenever the force exerted by the nippers in gripping the spike blank or bar is sufficient to overcome the friction exerted on the nipper frame by the shoes 70, the degree of force exerted by the nippers against the spike bar being determined as required, by varying the tension of the springs 72, which is effected by the adjustment of the bars 73.

Overrunning of the nipper frame due to its momentum, when the static friction of the shoes 70, which is much greater than the friction of motion, is overcome, is prevented by the check pistons 68, the resistance to whose movement in either direction is regulated as required by the adjustment of the valves 77.

The traverse of the nippers with the nipper frame being greater and hence at a more rapid rate, than the simultaneous advance of the jaws 26 and coöperating dies 6, the film of metal connecting the butt end of the spike body held by the nippers, and the point of the succeeding spike body held by the jaws and dies, is ruptured, and the spike body carried by the nippers is separated from the spike bar or body held between the clamping jaws.

With the initial backward movement of the friction connecting bars 52, the nippers are opened, and drop the spike body held between them into the channel in the upper side of the ejector 137, which then projects backward over the stationary die 83.

As the nipper frame with the nippers moves backward and the header bar 121 moves forward, the ejector 137 is withdrawn from the die 83 and the head 87 with the dies 88 and 89 is thrust downward by the action of the toggle joint 101, rocker arm 109 and cams 112. The die 88 is thus forced down upon the top of the spike body resting on the die 83, the ejector 137 having just been withdrawn as above stated by the forward movement of the header bar 121 leaving the spike body on the die 83, and the laterally movable dies 89 by engagement of their inclined faces 94 with the inclined faces 86 of the die 83, are forced toward each other against the sides of the spike body, which is thus firmly gripped and held by its

four sides with its butt end projecting from the front ends of said dies, as shown in Figs. 6 and 7.

The spike body being thus held by the gripping dies 83, 88 and 89, the swaging die 120 near the limit of its forward and upward movement, strikes the protruding butt end of the spike body with an upwardly glancing or sweeping blow, and forms a head thereon, as shown in Fig. 6, the gripping dies coöperating with the swaging die to produce a head of the desired shape. As the header bar 121 is swung backward and downward, and the dies 88 and 89 are withdrawn upward, the ejector 137 thrusts the headed spike backward and removes it from the stationary die 83 on which it loosely rests.

With each revolution of the drive shaft 17 the several operations hereinbefore mentioned are repeated, and a spike is formed and discharged from the machine upon the floor or into a receptacle below the bed 85.

Various modifications in the details of construction and arrangement of parts of the machine may be made without materially affecting its mode of operation and without departure from the principle of the invention as defined in the following claims.

30 I claim:

1. In a spike machine the combination with mechanism for forming and pointing spike bodies points foremost from continuous bars, of heading mechanism comprising gripping dies arranged to receive the spike bodies as they are delivered from the body forming and pointing mechanism, and a reciprocating swaging die movable into and out of the path of the spike bodies between the body forming and pointing mechanism and the gripping dies and adapted on its forward strokes to form heads on the spike bodies held by and projecting from the front ends of said gripping dies.

45 2. In a spike machine the combination with mechanism for forming and pointing spike bodies, of heading mechanism comprising gripping dies arranged to receive the spike bodies as they are delivered points foremost from the body forming and pointing mechanism, and a reciprocating swaging die adapted by obliquely delivered blows on its forward strokes to upset and form heads on the front butt ends of spike bodies held by the gripping dies, and a reciprocating ejector adapted on its backward strokes to remove headed spikes from the gripping dies.

60 3. In a spike machine the combination with pointing mechanism, of heading mechanism comprising a stationary die having opposing inclines, a reciprocating head movable toward and from the stationary die and provided with a relatively fixed die and two laterally movable dies located on opposite

sides of the fixed die and having inclines adapted by engagement with the inclines on the stationary die to force the laterally movable dies toward each other when they are moved toward the stationary die, and a reciprocating swaging die adapted on its forward strokes to form heads on the butt ends of spike bodies held by the other dies, and means for transferring the spike bodies from the pointing mechanism points foremost to the stationary die in position to be operated upon by the other dies.

4. In a spike machine the combination with intermittently rotated rolls and laterally opening and closing reciprocating jaws movable between and transversely to the axes of the rolls and coöperating with said rolls to form pointed spike bodies from continuous bars; of heading mechanism comprising a stationary die having opposing inclines, a reciprocating head movable toward and from the stationary die and provided with a relatively fixed intermediate die and two laterally movable dies having inclines adapted by engagement with the inclines on the stationary die to force said laterally movable dies toward each other when they are moved toward the stationary die, and a reciprocating swaging die adapted on its forward strokes to form heads on the front ends of spike bodies held between the other dies; and laterally opening and closing reciprocating nippers adapted to grasp and separate spike bodies from those held between said jaws and to transfer them to the stationary heading die in position to be operated upon by the other dies.

5. In a spike machine the combination with mechanism for forming spike bodies points foremost, of heading mechanism comprising a stationary lower die, a vertically movable upper die, laterally movable side dies movable with the upper die toward and from the lower die, a reciprocating swaging die adapted on its forward strokes to form heads on the front ends of spike bodies held between the other dies, and a buffer block engaging the rear end of the stationary die and adapted to receive the impact of the blows of the swaging die against the front ends of the other dies.

6. In a spike machine the combination with mechanism for forming spike bodies points foremost, of heading mechanism comprising a stationary die, a frame bed for supporting said die, a vertically movable die opposing the stationary die, laterally movable dies connected and movable with the vertically movable die, a longitudinally reciprocating swaging die adapted on its forward strokes to coöperate with the other dies and form heads on spike bodies held between them, a shouldered block mounted on said bed in position to bear against the back ends of the stationary and vertically and

laterally movable dies and to receive the impact of the blows of the swaging die against their front ends, and a cross bar supported at the ends by the machine frame and engaging the shoulder on said block.

5 7. In a spike machine the combination with mechanism for forming spike bodies points foremost, of stationary and vertically and laterally movable holding dies, a longitudinally reciprocating swaging die adapted on its forward strokes to cooperate with the front ends of the other dies to form heads on spike bodies held between them, a longitudinally channeled block mounted on the machine frame behind the stationary die and projecting above the same in position to receive the impact of the blows of the swaging die against the front ends of the holding dies, and a reciprocating ejector guided in

10 20 the channel of said block and adapted on its backward strokes to remove spikes from the holding dies when they are opened.

8. In a spike machine the combination with body forming mechanism and means 25 for transferring spike bodies therefrom points foremost, of heading mechanism comprising stationary and vertically and laterally movable holding dies arranged to receive the spike bodies from said transfer- 30 ring means, a longitudinally reciprocating header bar extending forwardly underneath the stationary holding die and having an upwardly offset front end, and a swaging die mounted on the front end of 35 said bar and movable therewith toward the front ends of the holding dies to form heads on spike bodies held between them with forwardly and upwardly sweeping blows.

9. In a spike machine the combination 40 of body forming mechanism comprising intermittently rotated rolls provided with opposing dies, a reciprocating carriage movable between and transversely to the axes of the rolls and provided with laterally open- 45 ing and closing clamping jaws working on opposite sides of the roll dies and capable of limited longitudinal movement relative to the carriage, two pairs of transversely disposed links connecting each jaw above 50 and below the same with the carriage, each link connecting pivot pins on the jaw and carriage and composed of strut and yoke members and of a U-bolt binding them together upon the pivot pins, and friction drag 55 connections between the jaws and stationary parts of the machine.

10. In a spike machine the combination of 60 body forming mechanism comprising a pair of shouldered rolls, radially slotted spacing rings fitted to the shoulders on the rolls, dies fitted in the slots of the spacing rings, cap rings fitting over the spacing rings and bolted therewith to the rolls, and set screws threaded in the cap rings opposite the slots

in the spacing rings for fastening the dies in 65 place.

11. In a spike machine the combination with body forming mechanism and heading mechanism, of mechanism for transferring spike bodies from the body forming 70 mechanism to the heading mechanism, comprising a reciprocating frame, laterally opening and closing nippers carried by said frame on opposite sides of the path of the spike bodies, actuating means connected 75 with the nippers and adapted to open and close them at the beginning of their forward and backward movements and through them to reciprocate said frame, and a cushion cylinder and piston one of which is connected with said reciprocating frame and the other with a stationary part of the machine.

12. In a spike machine the combination with body forming mechanism and heading 85 mechanism, of mechanism for transferring spike bodies from the body forming mechanism to the heading mechanism comprising a reciprocating frame, laterally opening and closing nippers connected with said frame, 90 actuating means connected with the nippers and adapted to open and close them at the limits of the backward and forward movements of said frame and then to pick up and move the frame backward and forward, a cushion cylinder and piston one of which is connected with said reciprocating frame and the other with a stationary part of the machine, and means for adjusting the fluid 95 resistance to relative movement between the 100 piston and cylinder.

13. In a spike machine the combination with body forming mechanism and heading mechanism, of mechanism for transferring spike bodies from the body forming 105 mechanism to the heading mechanism comprising a longitudinally reciprocating frame, transversely opening and closing nippers connected with said frame, actuating means with the nippers and adapted to open and 110 close them at the limits of the forward and backward movements of the frame and then to pick up and move the frame backward and forward, stationary cushion cylinders provided with check pistons connected with 115 the frame, and equalizing connections between the cylinders provided with vent openings to the atmosphere and with regulating valves.

14. In a spike machine the combination 120 with body forming mechanism and heading mechanism, of mechanism for transferring spike bodies from the body forming mechanism to the heading mechanism comprising a longitudinally reciprocating frame, 125 transversely opening and closing nippers connected with said frame, actuating means connected with the nippers and adapted to

open and close them at the limits of the forward and backward movements of the frame and then to pick up and move the frame backward and forward, a friction drag arm 5 ranged to resist the initial movement of the nipper frame, and a cushion cylinder and piston one of which is connected with said

reciprocating frame and the other with a stationary part of the machine and adapted to prevent its overrunning predetermined 10 limits of movement.

In witness whereof I hereto affix my signature.

LAURENCE J. BERKELEY.
